UNITED STATES PATENT OFFICE

LEANDER N. POND, OF KINGSPORT, TENNESSEE, ASSIGNOR TO BLUE RIDGE GLASS CORPORATION, OF KINGSPORT, TENNESSEE, A CORPORATION OF NEW YORK

APPARATUS FOR THE MANUFACTURE OF WIRE GLASS

Application filed September 6, 1930. Serial No. 480,253.

In a prior application filed by myself and Joseph H. Lewis on the 31st day of July, 1929, there is described a machine for the manufacture of wire glass in which the wire netting is fed into the glass in advance of the forming pass and moves through such pass with the glass and is there incorporated in the resultant sheet. The feed of the netting into the glass is accomplished by passing it between and in contact with the upper forming roller and a netting feed roller, the latter of which is but slightly above the hot glass. It has been found in practice that there is a tendency of the feeding roll to warp and to thus become concave on what at any time may be its lower side. Due to the fact that the netting feed roll is located below the horizontal plane of the center of the feed roll, this results in increasing the distance between the middle portions of the two rolls, so that the feed of the netting due to the feed roll is greater at the margin than at its middle. I have found that this can be avoided if the feed roll is bellied or enlarged at its center, as will be hereinafter described and claimed.

Referring to the accompanying drawings, in which corresponding parts are designated by corresponding marks of reference,—

Figure 1 is a vertical longitudinal section through a device embodying my invention; and

Figure 2 shows the netting feed rolls, the swelling of the middle portion thereof being exaggerated for purposes of illustration.

The machine represented in the drawing is that shown in the Lewis and Pond application with the improvement here sought to be protected.

A is the front wall of the furnace, having a feed opening B therein at the metal line, so that glass issues over the sill C to a forming pass D located between the upper and lower feed rolls E and F, respectively, and is there formed into a sheet which passes over the carrier roll K and between the polishing

rolls L and M. H is the netting feed roll and between it and the upper forming roll E the netting I is fed into the glass in advance of the forming pass. As described in the Lewis and Pond application, the position of the netting in the sheet is determined by the rate of feed of the netting as effected by the rolls E and H, and, as stated therein, it is desirable to have the roll H close to the glass. This results in the axis of the roll H being in a lower horizontal plane than the axis of the roll E. Under these conditions, any warping of the roll H due to the heat from the glass causes it to bend downwardly in the middle and, as a result, to cause its middle position to move away from the surface of the roll E.

According to this invention, the roll H, instead of being cylindrical as in the Lewis and Pond application, is enlarged at the central portion, so that such portion is bellied, as shown exaggerated in Figure 2. With this construction, the warping of the finishing roll, in lowering the middle portion thereof, causes the distance between the axis of the roll at the central portion and the adjacent surface of the forming roll to increase, thus giving room for the increased diameter of the finishing roll without causing the rolls to separate at their ends. Hence, constancy of spacing between the adjacent surfaces of the finishing roll and the forming roll is maintained, with consequent uniformity in the feed of the netting from side to side. The swell on the netting feed roll for this purpose need only be very small. For instance, in a roll used by me which having a glass working length of 48 inches, the radius at the center is .07 of an inch greater than the radius at the ends, which is 2.25 inches.

Having thus described my invention, what I claim is:

In a device for the manufacture of wire glass, the combination with forming rollers having a forming pass between them, means

for feeding glass to the forming pass, a netting feed roll adjacent to the upper forming roll, the two having a space therebetween for the passage of netting, the axis of the netting feed roll being in a horizontal plane below that of the upper forming roll and the netting feed roll having its center swelled in respect to its ends.

In testimony whereof I hereunto affix my
10 signature.

LEANDER N. POND.
